UNITED STATES PATENT OFFICE.

JULES ANDRÉ SMITH, OF PINE ORCHARD, CONNECTICUT.

DESIGN FOR AN ASH TRAY.

Application filed July 30, 1927. Serial No. 22,963. Term of patent 14 years.

To all whom it may concern:

Be it known that I, JULES ANDRÉ SMITH, a citizen of the United States, and a resident of Pine Orchard, New Haven County, Connecticut, have invented a new, original, and ornamental Design for an Ash Tray, of which the following is a specification, reference being had to the accompanying drawing, forming part thereof.

The drawing is a perspective view of an ash tray illustrating my new design.

I claim;

The ornamental design for an ash tray substantially as shown.

In testimony whereof, I have hereunto signed this specification.

J. ANDRÉ SMITH.
